The ornamental design for an aircraft cabin, as shown and described.

DESCRIPTION

FIG. 1 is a perspective view of an aircraft cabin showing our new design; and,

FIG. 2 is a side elevational view taken from the longitudinal center of FIG. 1.

The structural elements depicted by broken lines have been shown for purposes of illustrating portions of the aircraft cabin that form no part of the claimed design.

The dot-dash lines in FIGS. 1 and 2 represent the boundaries of the claim and form no part thereof.
